UNITED STATES PATENT OFFICE.

JOSEPH B. NEFF, OF BURLINGTON, IOWA, ASSIGNOR TO THE HAPGOOD
PLOW COMPANY, OF ALTON, ILLINOIS.

PLOW.

SPECIFICATION forming part of Letters Patent No. 380,658, dated April 3, 1888.

Application filed January 13, 1888. Serial No. 260,624. (No model.)

To all whom it may concern:

Be it known that I, JOSEPH B. NEFF, a citizen of the United States, residing at Burlington, in the State of Iowa, have invented a new 5 and useful Improvement in Plows, of which the following is a specification.

My invention relates to plows having a beam, with handles connected to the beam, and has the object to improve the method of adjusting to the beam, so that the beam may be more readily moved and adjusted and be made either for three-horse or for two-horse working, as may be desired.

Referring to the drawings, like letters referring to like parts in all the figures, Figure 1 is a top view of an ordinary plow with my improvement connected therewith in the block *a*, interposed between the handle and beam. Fig. 2 is a land-side elevation view of same, 20 showing how the said block may be moved to the outside of the handle. Fig. 3 is a rear end view of the plow shown in Fig. 1. Fig. 4 is a detail view, enlarged, of the parts, same as is shown in Fig. 1. Fig. 5 is a perspective 25 view, enlarged, of the block *a*; and Fig. 6 is a detail view showing the block attached to the inside of the beam, where it may be carried when not in use otherwise.

My improvement may be used in plows of 30 any ordinary construction having the plow *B*, with the standard *C*, the beam *A*, and the handles *H*, all of ordinary construction, except as modified to embrace my invention, as shown in the drawings. The said beam has a recess 35 or gain, *b*, as ordinary, cut in one side of its rear end, and the handle has been directly seated in said gain and secured thereto by a bolt through both handle and beam.

a represents my improved adjusting-block, 40 preferably constructed of iron, about one inch thick, and it may be chambered out to lighten its weight, and of an outline diamond-shaped of about the same shape as the seat of the said gain, and with a slotted perforation, *c*, as will be understood by the drawings. The said perforation *c* is preferably made long slotted to adapt the block for its interchangeable use, as hereinafter shown.

In constructing my improved plow I usually 45 put the parts together as shown in Fig. 2, in

which the handle is seated directly in the said gain and the said block placed outside of the handle, with the bolt *e* seated through the three parts, holding them securely together, and when the block is so used outside of the 55 handle it materially strengthens the handle at what was before the weakest place in the handle, in which condition the front end of the beam is set from land for a two-horse plow, as shown by dotted lines in Fig. 1. Then, when 60 desired to adjust same and make it set for three-horse plow, the bolts securing the standard are first loosened, then the bolt *e* removed, the block moved and interposed between the handle and beam, and the same bolt, *e*, returned 65 through the three—handle, block, and beam; then the standard-bolts again tightened and the beam made secure in its new position, with its front end over land for a three-horse plow, as shown in Fig. 1, avoiding all springing and 70 warping of the handle.

It will be observed that the handles are attached to the plow and connected by the brace rungs or rods *m*, as usual, and that the one handle is a brace and support to the other 75 through said rods, and forming a rigid support for the rear end of the beam. It will also be observed that when the beam is loosened in its standard-connection and the handle-securing bolt removed the beam is free to swing and be 80 moved without warping, springing, or twisting the said handles, or any other part of the plow, and also that the said block may be used either between the handle and beam or outside of the handle, with the same bolt connecting them. It is obvious that the said block 85 may be placed on the inside of the beam to be carried, as shown in Fig. 6, in which case the same securing-bolt may be used, as before.

I am aware that blocks and wedges have 90 heretofore been used to point the beam to or from land. Such I do not broadly claim; but I am not aware of any heretofore use of an interchangeable block interposed between the beam and handle, seated in a recess formed in 95 the beam, with a bolt passing through the three parts—handle, block, and beam—as herein shown and claimed.

Having thus set forth my invention, I claim—

The interchangeable block provided with 100

the slotted perforation, adapted to be used on the outside of the handle as a strengthening-support to the handle, or interposed between the handle and beam in converting the plow 5 into a three-horse plow, or placed on the inside of the beam to be carried, in combination with a beam provided with a recess on the side of its rear end, a handle seated in said recess,

and a bolt seated through the said three parts—handle, block, and beam—substantially to as and for the purpose set forth.

JOSEPH B. NEFF.
